UNITED STATES PATENT OFFICE.

THOMAS HARDING AND BERNARD BIEHL, SR., OF NEWARK, NEW JERSEY, ASSIGNEES
TO J. L. SOMMER MANUFACTURING CO., A CORPORATION OF NEW JERSEY.

CAN-OPENING WRENCH.

Application filed April 5, 1922. Serial No. 549,790.

To all whom it may concern:

Be it known that we, THOMAS HARDING and BERNARD BIEHL, Sr., both citizens of the United States, and residents of Newark, 5 in the county of Essex and State of New Jersey, have invented new and useful Improvements in Can-Opening Wrenches, of which the following is a specification.

The objects of this invention are to provide an improved wrench more especially for opening that class of cans, jars, bottles or the like, which have screw tops or caps; to provide such a wrench which shall be capable of fitting a large range of sizes of such caps or tops, and engage them all firmly and securely; to enable the wrench to be quickly and easily applied to tops or caps of various sizes, without any particular care or adjustment; to secure such an arrangement of the 10 jaws for smaller tops or caps, with respect to the other jaws, that they serve as a stop to engage the top or cap and position the wrench; to strengthen the jaws of the wrench so that they will not spring or twist 15 out of their proper plane; to effect such strengthening by having the jaws for the smaller sizes of tops or cap reenforce the jaws for larger sizes, and to obtain other results and advantages as may be brought out 20 by the following description.

Referring to the accompanying drawings, in which like numerals of reference indicate the same parts throughout the several views,

Figure 1 is a plan view of our improved 25 wrench applied to a large-sized can top or cap;

Figure 2 is an edge view of the wrench;

Figure 3 is a side view of the can top shown in Figure 1, and

Figure 4 is a detail view illustrating the 30 operation of a pivotal link connecting the jaws.

In said drawings 1, 1 indicate the two 35 jaws of our improved wrench, each comprising heavy sheet metal sections joined as hereinafter described, two adjacent ends of said jaws being pivotally connected by a link 2 and the other two ends provided with handles 3, 3 by which the jaws are manipulated.

Each jaw portion 4 is provided at one 40 side of the wrench with an auxiliary portion 6 disposed in a chordal relation to the portion 4 and extending from the pivotal connection of the jaws to the link 2 at a

point adjacent the union of the handle 3 with the main portion 4 of the jaw, these two auxiliary or chordal portions 6, 6 being provided at their adjacent edges with serrated concaves 7, 7 and 8, 8, the two 8, 8 farthest from the pivoting of the jaws being of greater radius and adapted to grasp a can top or cover somewhat smaller than that grasped by the main portion 4, 4 of the jaws, and the curve 7, 7, next the pivoting of the jaws being of less radius to grasp a still smaller top or cap.

Each chordal portion 6 receives at one end, between itself and the end of the main portion 4, one end of the link 2, and a pivot 9 for said link extends through all three parts, being headed or riveted over at its ends to hold them together and yet permit free pivotal movement. The other end of each chordal portion 6 is secured to the 75 main portion 4 by a double-ended rivet having a washer-like body portion 10 which lies between the portions 4 and 6 as does the link 2, so as to hold them parallel, and has its two reduced ends extending through 80 perforations in said portions 4 and 6 respectively and riveted as at 11 and 12 to hold said portions firmly and rigidly together.

The small serrated curves 7, 7 and 8, 8 of 85 the auxiliary or chordal portions 6 are thus disposed or set inwardly from the serrated curves of the main portions 4, so that when they can engage small caps the other serrations are idle, and by reason of the chordal 90 and rigid relation of said auxiliary portions 6, 6 with reference to the main portions 4, 4, they brace and reenforce said main portions against any tendency to spring or twist under severe pressure in moving a large-sized top or cap. This is a very important feature of our invention, since it has been found impossible to make a wrench of as light stock as we employ which would not spring or twist under severe usage.

In applying the wrench to a large can top or cap, it will be noticed that the chordal portions 6, 6 lie on the top of the cap, as shown in Figure 2, and automatically position the large jaws on said cap. In using 105 the two smaller sizes of jaws, the wrench can either be used the same side up, or if the large jaws are for any reason in the way, the wrench can be turned over and used the other side up.

2
 The link 2 not only positions the jaws of our wrench so that they engage on nearly diametrically opposite sides of a top or cap, but it also ensures such positioning of the jaws regardless of their relative position when applied to the top or cap. That is to say, if the jaws are not symmetrically opposite but somewhat out of such relation as shown in full lines in Figure 4, when applied to a top or cap, pressure upon the handles will automatically draw them into the desired opposite relation, as shown in dotted lines in said Figure 4, without any particular attention or voluntary adjustment by the operator. Preferably one of the chordal or auxiliary jaw portions 6 is extended at the pivotal end of the wrench and shaped into a bottle opener 13, and the free extremities of the handles 3, 3 are also preferably made wedge-shaped as at 14 for insertion beneath the flange of a friction can top such as is used to contain many articles for the kitchen or household.

Various detail modifications and changes can be made by those skilled in the art in the manufacture of our improved wrenches without departing from the spirit or scope of the invention, and we do not wish to be understood as limiting ourselves except as required by the following claims when construed in the light of the prior art.

Having thus described the invention, what we claim is:

1. In a wrench, the combination of gripping jaws pivotally connected at two of their adjacent ends and having handles at their other ends, said jaws comprising cooperating main portions oppositely bowed apart and chordal portions on said main portions offset from the plane thereof, all said portions having their oppositely adjacent edges adapted to grippingly engage an article.

2. In a wrench, the combination of gripping jaws pivotally connected at two of their adjacent ends and having handles at their other ends, said jaws comprising cooperating main portions oppositely bowed apart and chordal portions secured at their ends thereto and spaced therefrom at their middle portions, all said portions having their oppositely adjacent edges adapted to grippingly engage an article.

3. In a wrench, the combination of gripping jaws pivotally connected at their ad-

jacent ends and having handles at their other ends, said jaws each comprising spaced parallel portions having arcuate oppositely adjacent edges to grippingly engage an article, the oppositely adjacent arcuate edges in different planes being formed with different radii to grippingly engage articles of different sizes.

4. In a wrench, the combination of gripping jaws pivotally connected at their adjacent ends and having handles at their other ends, each of said jaws comprising a main portion and an auxiliary portion secured to said main portion in spaced and substantially parallel relation thereto and extending from the point of pivotal connection of said jaws substantially to the handle, both said portions having their oppositely adjacent edges formed to grip an article.

5. In a wrench, the combination of gripping jaws pivotally connected at their adjacent ends and having handles at their other ends, said jaws comprising cooperating main portions oppositely bowed apart and longitudinal reenforcing portions on said main portions, both said main portions and reenforcing portions having their oppositely adjacent edges adapted to grippingly engage an article.

6. In a wrench, the combination of gripping jaws pivotally connected at their adjacent ends and having handles at their other ends, said jaws comprising cooperating main portions oppositely bowed apart and longitudinal reenforcing portions on said main portions offset from the plane of the main portions, oppositely adjacent edges of said main portions and of said reenforcing portions being formed on different radii to grip an article.

7. In a wrench, the combination of gripping jaws pivotally connected at their adjacent ends and having handles at their other ends, said jaws comprising cooperating main portions with gripping edges oppositely bowed apart and longitudinal reenforcing portions on said main portions offset from the plane of the main portions and having each a plurality of gripping arcs of different radii to engage articles of different sizes.

THOMAS HARDING,
BERNARD BIEHL, SR.
